UNITED STATES PATENT OFFICE.

MARTIN JELALIAN, OF CRANSTON, RHODE ISLAND.

HYDRO-AERIO GLIDING APPARATUS FOR AERIAL AMUSEMENT PURPOSES.

1,186,580.

Specification of Letters Patent. Patented June 13, 1916.

Application filed February 23, 1916. Serial No. 79,984.

To all whom it may concern:

Be it known that I, MARTIN JELALIAN, a citizen of the United States, residing at the city of Cranston, in the county of Providence and State of Rhode Island, have invented certain new and useful Improvements in Hydro-Aerio Gliding Apparatus for Aerial Amusement Purposes, of which the following is a specification.

10 This invention relates to an aerial apparatus essentially designed for amusement purposes, having a gas bag capable of lifting and sustaining the operator, an independent winged device for assisting the operator in driving the apparatus forward, and a buoyant structure attachably secured to the body of the aviator for permitting the latter to float upon the surface of the water.

15 The invention consists in the special features of the construction and combination of parts, as hereinafter described and claimed.

20 In describing the invention reference is had to the accompanying two sheets of drawings, in which:—

25 Figure 1 is a front elevation of my improved apparatus, showing one form of balloon or gas bag for the same; Fig. 2 is a rear elevation of the apparatus, as equipped with another form of balloon; Fig. 3 is a front view of the combined independent winged device and buoyant structure, as secured in position upon the aviator; Fig. 4 is a rear elevation of Fig. 3; Fig. 5 is a perspective view of the bottom frame for the semi-spherical form of balloon; Fig. 6 is a perspective view of the detachable abdominal support of the buoyant structure of the apparatus; Fig. 7 is a top view of the winged device; Fig. 8 is a perspective view of the buoyant structure, showing the same equipped with oars for use by the aviator.

30 Referring to the drawings, the numeral 1 designates a metallic ring, which is of a channel shape and said ring surrounds a wire netting 2 and beneath the latter is a layer of canvas 3, the whole forming a frame (see Fig. 5,) which is suitably connected to the surrounding edge of the balloon or gas bag 3 and serving as a plane for the apparatus.

35 To reinforce the bag 3 and prevent the same from bursting, when inflated with

gas, ropes 6 have their ends attached in a suitable manner to the ring 1 and are 55 connected at a central point, as at 5, and also by lateral circumferentially-arranged ropes 4.

Connected to the lower ledge of the ring 1 is a plurality of converging ropes 60 7, whose lower ends are connected to the upper edge of a small ring 8, of form similar to that of the upper ring 1. Ropes 9 have their upper ends connected to the lower edge of the small ring 8, 65 and the opposite ends of said ropes are connected to spring snap-hooks 25 of the abdominal buoyant structure, shown in Fig. 4. The hooks are attached to equi-spaced eyelets 16 surrounding the upper portion 70 of the abdominal support 17. The support 17 is attached to the abdominal part of the operator 22, by means of straps 27 at the front part thereof, and also by attaching means in the back, as at 75 28. The lower part of the support 17 is also provided with straps 20 for securing to the lower part of the body of the operator, in order to aid in suspension. The inner surface of the support 17 is 80 provided with a pad of yielding material 29, as shown in Fig. 6. The small ring 8 is also provided with wire netting and canvas, in the same manner as the frame of the gas bag 3 and also serves as a 85 plane.

At the central portion of the support 17 is made fast a supporting hoop 30, to which are bolted, as at 31, surrounding wing supports 26 upon 90 which is secured a surrounding stationary lateral wing 18, designed to react against the atmosphere and to serve as a plane. Projecting outwardly from the aviator 22 and above the surrounding stationary wings 18 is a pair of bird-like wings 10, which are provided with arm fitting supports 11 having suitable clasp buttons for securing to the arms of the aviator. The inner ends of the wings 18 have 95 spring connection 23 with a suitable shoulder support 13, having straps 15 and an attaching belt for securing to the body of the aviator, in the manner shown in Figs. 1, 2, 3 and 4.

100 The wings 10 may be easily flapped

by the aviator, to assist the gas bag in making a more rapid ascension, and means is also provided for him to let free his arms from the holding strap —12— and arm-fitting support —11—, to freely use his arms for whatever purpose he may desire.

Extending outwardly from the aviator and above the shoulder fitting support —13— is an outwardly-projecting circular hat —9— having straps and suitable securing means for attaching to the head of the aviator. The hat has a projecting plane designed to react against the atmosphere and to serve as a plane above the wings —10—.

In Fig. 7 is shown the spring attachment, and wherein —31— designates a pair of vertical supports which are secured upon the sides of the shoulder fitting support —13—, and coil pull-springs —30— have their upper ends secured to said supports and the lower ends thereof attached to the wings —10—.

I illustrate two forms of gas bags, as by Figs. 1 and 2, in order to make clear that either form may be employed in the construction of the apparatus, although the bag —3— is preferable in view of its frame affording a vast surface against downward resistance by the atmosphere. Each balloon or gas bag is provided with a flexible tube connection —3²— having a suitable valve within easy reach for use by the operator, so as, when necessary, to permit the gas to escape from said tube in making a descent.

In the construction of the abdominal support —17— the latter is provided with a circular plane consisting of a rim —26¹— having stays —26— which radiate from the band —30—, secured upon said support —17—, and the said stays are covered by a layer of canvas —18—, thus forming a frame to serve as a plane for said support, in the manner shown in Fig. 4.

In order that the apparatus may be utilized by the operator in performing upon the surface of the water, the plane, of the abdominal support, is provided with two cylinders —12¹— which are secured beneath said plane (see Fig. 1,) by means of straps —13²—, and said cylinders have suitable tube and valve connections for the operator's use in forcing air into said cylinders, and thereby providing buoyancy for the said abdominal support structure. The buoyant plane —18— may also be provided with locks —11¹— to receive oars —19¹—, for use by the operator in propelling himself through the water, in the manner shown in Fig. 8.

By this construction and arrangement of parts I provide an apparatus that appeals to outdoor sport; which will afford attractive amusement, safe in its operation,

and at the same time having the utility of being employed for either aerial or aquatic use.

Having described my invention, what I claim and desire to secure by Letters Patent, is—

1. In an apparatus of the character described, a gas bag having a flat bottom to serve as a plane; an abdominal support for the aviator, said support centrally of a circular plane carrying cylinders adapted to receive air under pressure; a winged device adapted to be secured to the arms of the aviator, and said device having pull-spring connections to facilitate the upward movement of the wings; a small plane intermediate the said bag and the said abdominal support, and rope connections from said bag to said last mentioned plane and also from the latter to said support. 85

2. In an apparatus of the character described, a gas bag having a flat bottom to serve as a plane, said plane consisting of a ring having a channel so as to provide two outwardly-projecting ledges having equi-spaced perforations, a layer of wire netting secured to the ring, and a layer of canvas secured to the latter, respectively; a buoyant plane having an integral central abdominal support provided with straps for securing to the body of the aviator; ropes from the bag and having their ends secured in the perforations of the upper ledge of the ring; an intermediate small plane between the above-mentioned planes; rope connections from the perforations in the lower ledge of the ring to the said small plane, and rope connections from the latter to securing means carried by the support of the buoyant plane. 100

3. In an apparatus of the character described, a gas balloon; an abdominal support for the aviator, said support having strap connections for securing around the legs of the latter, and said support carrying a plane consisting of a hoop having stays radially secured to a band surrounding the said support and a canvas cover secured to said stays, cylinders carried beneath the plane and adapted to receive air under pressure; rope connections from the bag to said abdominal support, and a small circular plane carried by the rope connections and located at a point above the aviator. 110

4. In an apparatus of the character described, an abdominal supporting structure having straps for attachment at the front and back, and to the leg parts of the aviator, said structure integral with and centrally of a circular plane; buoyant means carried beneath the said plane; a pivotal winged device designed to be secured upon the shoulders of the aviator and provided with yielding means to assist the upward movement of the wings; a hat having suitable strap 125

connections for securing to the head of the operator and said member having an integral circular plane to co-act with the main plane against upward resistance of the atmosphere.

5. In an apparatus of the character described, a gas bag, a propelling means consisting of a support designed to fit upon the shoulders of the aviator, a pair of bird-like wings pivoted to said support, clasps carried by the wings for securing to the arms of the aviator, and pull-spring connections to assist the upward movement of the wings, respectively; an abdominal support for the aviator, and said support having encircling equi-spaced snap-hooks; rope connections from the bag to the hooks of said abdominal support, and a flexible tube having a valve to permit the escape of gas from said bag.

6. In an apparatus of the character described, an abdominal support having an

integral main plane; buoyant means carried by the latter; row-locks secured upon the top of the plane and having oars mounted within the same; a winged means carried upon the shoulders of the operator to permit the latter to make a propelling forward movement; a gas balloon having rope connections to the said support; a small plane intermediate the operator and the balloon, and said plane consisting of a metallic ring having a surrounding channel provided with equi-spaced perforations for attaching the ropes of the balloon thereto; a wire netting secured to said ring, and a canvas carried upon the netting.

In testimony whereof I affix my signature in presence of two witnesses.

MARTIN JELALIAN.
